CARRIER FOR SURGICAL SUTURES

Gordon E. Caraway, Dallas, Tex.

Application December 14, 1951, Serial No. 261,710

6 Claims. (Cl. 206—63.3)

1

This invention relates to surgical appliances and more particularly to a means for storing suture material for immediate accessibility when needed for surgical uses.

The principal object of the invention is to supplant the conventional and unsatisfactory practice of preparing suture material for surgical purposes consisting generally of winding the threads on a piece of cardboard, stick or the like for sterilization in an autoclave, by providing a carrier in the form of a flexible web, preferably gauze material of indeterminate length and by attaching to the gauze coextensive lengths of suture material, the threads being spaced apart on the gauze in groups of predetermined number. The gauze may be readily unrolled or unfolded, as the case may be to expose the suture threads whose lengths may be predetermined for use by cutting the gauze transversely, whereupon the severed portions may be placed in an autoclave or other sterilizing device until required for surgical use.

Broadly, the invention seeks to provide a more convenient medium for storing, preparing and sterilizing suture material for surgical use which relieves the hospital attendant of the annoying and time consuming duty of winding the suture threads onto makeshift supports for sterilizing, and the equally unsatisfactory practice of individually cutting the suture threads into lengths as prescribed by the surgeon.

With the foregoing and other objects in view, the invention has reference to certain features of accomplishment which will become manifest in the following description taken in connection with the accompanying drawing wherein:

Figure 1 is a perspective view showing a roll of fabric material such as surgical gauze into which parallel groups of suture threads are woven for ready release therefrom.

Figure 2 is a fragmentary plan view.

Figure 3 is a fragmentary view of the suture carrier in longitudinal section showing one form of attaching the suture threads thereto; and

Figure 4 is a perspective view showing the carrier folded in zig-zag fashion.

Continuing with a more detailed description of the drawing, numeral 10 denotes a carrier consisting preferably of a surgical gauze web of indeterminate length and of predetermined width. The carrier 10 is connected for ready detachment a plurality of groups of suture threads 11 which are coextensive with the gauze carrier 10. The preferred method of attaching the suture threads to the gauze carrier is to weave the threads through the loosely woven fabric of the

carrier, in the manner shown since this method of attaching the suture threads enables the latter to be drawn smoothly from the carrier when severed.

The groups of suture threads 11 are arranged in parallel relationship across the fabric carrier 10 in order that one or more groups of threads of predetermined lengths may be detached from the carrier by cutting the latter longitudinally to separate the required number of groups from the remaining groups of threads by cutting the carrier transversely to predetermine the length of the selected group or groups of threads. The unsevered portion of the carrier may be re-rolled or re-folded, depending upon the manner in which the suture material is stored. The severed portion of the carrier with the attached threads is then placed in an autoclave or other sterilizing device. The carrier is placed in a convenient location until additional suture material is needed.

In Figure 1 the suture carrier is shown as being formed in a roll while in Figure 4, the identical carrier is shown as being folded in zig-zag fashion. In either case, the carrier may be confined within a suitable container and drawn from the container as suture material is needed. In this manner, the suture material is shielded from foreign matter and kept in a sanitary condition.

It is intended that the invention shall include any suitable material other than woven fabric as a carrier and that the suture threads may be attached to the carrier in any suitable manner other than the weaving in the manner set forth herein. Moreover, the suture material itself may consist of cotton threads, silk threads, nylon threads or any other type of suture material which may be stored in the manner anticipated by the invention.

What is claimed is:

1. In a carrier for suture threads for surgical use, a web of gauze material and a plurality of lengths of suture threads interwoven longitudinally through said web and adapted to be made into usable lengths by severing said web to correspondingly sever said suture threads.

2. In a carrier for suture threads adapted for surgical use, a surgical gauze web of greater length than width and a plurality of groups of suture threads interwoven with said web lengthwise thereof, said groups being spaced apart for separation one from another by longitudinal severance of said web between said selected groups of threads and for detachment into usable lengths by transverse severance of said web.

3. A carrier for suture material comprising a web of flexible material of predetermined width

and indeterminate length and a plurality of groups of suture threads coextensive with the length of said web, the suture thread of each of said groups being separate one from another and extended repeatedly through said web from one side to the other at a series of points throughout the length of said web, to hold said threads against lateral detachment from said web, said threads capable of longitudinal displacement when said web is severed transversely.

4. A carrier for suture material comprising a web of flexible material and a plurality of separated strands of suture material extending back and forth through said web from one side to the other thereof at a plurality of points spaced longitudinally of said web, said suture threads being adapted to be cut into predetermined lengths by transverse severance of said web.

5. In a carrier for suture threads for surgical use, a web of woven fabric of predetermined width and indeterminate length and a plurality of individually separated suture threads extending repeatedly through said web from one side to the other thereof in relative parallelism with

each other and with the longitudinal axis of said web.

6. In a carrier for suture threads adapted for surgical use, a web of flexible material of greater length than width and a plurality of groups of suture threads interwoven with said web lengthwise thereof, each group comprising a plurality of threads in separated and parallel relationship, said groups being spaced apart for separation one from another by longitudinal severance of said web between said selected groups of threads and for detachment into usable lengths by transverse severance of said web.

GORDON E. CARAWAY.
